UNITED STATES PATENT OFFICE.

EDMUND SIGWALT, OF STORM LAKE, IOWA.

ELECTRIC SIGN.

Application filed May 25, 1925. Serial No. 32,798.

The present invention has reference to changeable exhibitors and aims to provide a changeable exhibitor wherein the letters making up the words constituting an advertisement or the like, may be illuminated for night advertising.

Another important object of the invention is to provide a device of this character which includes a plurality of endless webs constructed to provide boxes for the reception of electric lamps to illuminate the interiors thereof.

A still further object of the invention is to provide endless belts having all the letters of the alphabet thereon, the belts being arranged in parallel relation with each other so that when certain letters are moved to their displaying positions, the combination of letters will constitute words.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view of a sign constructed in accordance with the invention, the endless belts having been moved to spell words.

Figure 2 is a plan view thereof.

Figure 3 is a longitudinal sectional view through one of the display sections of the device.

Referring to the drawings in detail, the device comprises a frame that includes spaced vertical bars 5 that are connected by means of the bars 6 and bars 7 mounted thereabove, the bars 6 being provided with a plurality of openings to accommodate the shafts 8 that are arranged in parallel spaced relation with each other and provided with beveled pinions 9 that mesh with beveled pinions 10 mounted on the shafts 11.

Rollers 12 are mounted on the shafts 11 and provide supports for the endless webs 13 that operate thereover. At the forward end of the frame are rollers 14 over which the forward portions of the endless webs 13

move, the rollers 14 acting to hold the webs in extended positions.

These webs are supplied with the letters of the alphabet, the letters being cut out providing openings to allow light rays to pass therethrough outlining the letters and words spelled by the letters.

Lamps 15 are supported adjacent to the forward end of the frame, there being provided a lamp disposed within the confines of the respective endless webs, to the end that the letters moved to the forward portion of the frame will be properly illuminated.

As before stated, these webs operate vertically and in parallel relation with each other the sides of the web defining elongated box-like members within which the lamps are positioned. Finger pieces 16 are arranged at the forward ends of the shafts 8 whereby the shafts 8 may be rotated to impart rotary movement to the beveled pinions 9 and 10 in order that the endless webs may be rotated to bring certain letters to the forward portion of the frame for spelling a particular word used in advertising.

It might be further stated that a plurality of these endless webs are arranged one above the other and the number of webs used on a device of this character may be varied to meet the requirements of usage.

I claim:

A changeable exhibitor including a frame, vertically spaced bars at the front of the frame defining display openings, pairs of transversely spaced vertical rollers mounted between the bars at the front of the exhibitor and adjacent to the display openings, a plurality of spaced vertical rollers at the rear of the exhibitor and disposed directly behind the first mentioned rollers, an endless web passing over each pair of rollers and passing over one of the vertical rollers at the rear of the frame, said webs having letters formed therein, and means for rotating the rollers at the rear of the exhibitor for moving the webs to display letters at the display opening associated therewith.

In testimony that I claim the foregoing as my own, I have hereto affixed my signature.

EDMUND SIGWALT.
